UNITED STATES PATENT OFFICE.

RICHARD SCHOUTEN, OF KEOKUK, IOWA.

KNOCKDOWN CASE.

SPECIFICATION forming part of Letters Patent No. 763,801, dated June 28, 1904.

Application filed January 7, 1904. Serial No. 188,051. (No model.)

To all whom it may concern:

Be it known that I, RICHARD SCHOUTEN, a citizen of the United States, and a resident of Keokuk, in the county of Lee and State of Iowa, have invented a new and Improved Knockdown Case, of which the following is a full, clear, and exact description.

This invention relates to improvements in cases or boxes particularly adapted for shipping bread or the like, an object being to provide a case that will be light yet strong and durable and so constructed that it may be compactly folded to take up but little space during the return shipment or in storage.

I will describe a knockdown case embodying my invention and then point out the novel features in the appended claims.

Reference is to be had to the accompanying drawings, forming a part of this specification, in which similar characters of reference indicate corresponding parts in all the figures.

Figure 1 is a perspective view of a knockdown case embodying my invention. Fig. 2 is a vertical section thereof. Fig. 3 is a horizontal section. Figs. 4 and 5 are respectively a side and an end elevation of the case as folded, and Fig. 6 is a sectional view of a hinge connection employed.

The case comprises opposite side walls 1, 2, a front wall 3, and a rear wall 4. Each wall consists of sheathing, the sheathings being of thin strong wood. In each wall the sheathings are secured to an upper bar 5, a lower bar 6, and an intermediate bar 7. It will be noted that the bars of the front wall overlap the ends of the bars connected to the side walls and also that the bars of the back wall overlap the ends of the side-wall bars.

Secured to the upper and lower sides of the front bars and to the rear bars at diagonally opposite corners are L-shaped hinge-plates 8. The short members of these hinge-plates overlap the bars of the side walls, and through perforations in these short portions pivot-rods 9 extend, the said rods of course also extending through the bars of the side walls, and they also project slightly below the bottom of the box, and the projected ends are rounded, as indicated at 10, forming supports that may be easily slid over the floor when it

is desired to move the case from place to place. At the other corners hinge-plates 11 are secured to the upper and lower sides of the bars of the side walls, and their perforated ends overlap the bars of the front and rear walls, and through the perforations of these overlapped ends pivot-rods 12 extend similar to the pivot-rods 9. The bottom board 13 for the case has hinged connection 14 with the inner side of the rear wall, so that said bottom board may be swung upward against the inner side of said rear wall. When in its lowered position, the bottom board will rest on cleats 15, secured to the several walls. This bottom board is locked in its lowered position by bolts 16 sliding thereon and engaging in recesses 17 in the front bottom bar 6. A cover 18 is so hinged to the rear upper bar 5 that when it is desired to fold the case the said cover may be turned against the outer side of the rear wall. The cover is provided with a hasp 19 for engaging with a staple 20 on the front top bar 5. At the portion where the L-shaped hinge-plates are arranged the sheathings of the side walls are provided with slots 21, which permit the movements of the hinges. When in use, the bottom board will keep the side walls in proper position, and to aid the same the cover at its inner side is provided with batten-strips 22 for engaging against the inner side of the several walls.

When not in use, the bottom board is to be turned upward against the inner side of the wall to which it is hinged, the cover folded against the outer side of the wall to which it is hinged, and then the several walls may be swung together, as indicated in Figs. 4 and 5. The L-shaped hinges permit the walls to be folded in parallelism, and therefore several cases may be readily packed together one upon another.

Having thus described my invention, I claim as new and desire to secure by Letters Patent—

1. A knockdown case comprising four walls, each wall consisting of sheathing of thin material, horizontally-disposed bars on the outside of the box to which the sheathings are connected, the ends of the bars of the front and rear walls overlapping the ends of the bars of the side walls, L-shaped hinge-plates

at two of the diagonally opposite corners of the box having their longer sides connected to the upper and lower sides of the front and rear bars with their shorter sides overlapping 5 the top and bottom sides of the end bars, said shorter sides being provided with apertures at their ends, plates attached to the upper and lower sides of the horizontal bars at the other diagonally opposite corners of the box, the 10 ends of said plates lapping the top and bottom sides of the front and rear cross-bars and provided at said overlapping ends with apertures, said cross-bars having vertical apertures at their corners registering with the apertures in 15 said latter plates and the shorter ends of the L-shaped plates, rods extending downwardly through said registering apertures outside the sheathing of the box to form hinges, the end sheathings at points opposite the inner edge 20 of the shorter side of the L-shaped plate being provided with apertures of a size to permit the passage of said ends when the box is folded, a bottom board hinged to the inner side of one of the walls and adapted to open 25 upwardly against said wall when the box is folded, batten-strips attached to the inner sides of the walls to support said bottom boards when lowered to position, the bottom bar and sheathing having a recess at the free 30 edge of the bottom flush with the top side thereof, bolts slideable on said bottom and movable into said recesses to lock the bottom in operative position, a cover hinged to one of the walls, and batten-strips on the inner side 35 of said cover for engaging the inner top edges of the walls, said cover being adapted to fold outwardly against the rear side of the box.

2. A knockdown case comprising four walls, each wall consisting of sheathing of thin material, horizontally-disposed bars on the 40 outside of the box to which the sheathings are connected, the ends of the bars of the front and rear walls overlapping the ends of the bars of the side walls, L-shaped hinge-plates at two of the diagonally opposite corners of the box 45 having their longer sides connected to the upper and lower sides of the front and rear bars with their shorter sides overlapping the top and bottom sides of the end bars, said shorter sides being provided with apertures at their 50 ends, plates attached to the upper and lower sides of the horizontal bars at the other diagonally opposite corners of the box, the ends of said plates lapping the top and bottom sides of the front and rear cross-bars and provided 55 at said overlapping ends with apertures, said cross-bars having vertical apertures at their corners registering with the apertures in said latter plates and the shorter ends of the L-shaped plates, and rods extending downwardly 60 through said registering apertures outside the sheathing of the box to form hinges, the end sheathings at points opposite the inner edge of the shorter side of the L-shaped plate being provided with apertures of a size to permit the passage of said ends when the box is 65 folded.

In testimony whereof I have signed my name to this specification in the presence of two subscribing witnesses.

RICHARD SCHOUTEN.
